YARN AND METHOD OF PRODUCING
THE SAME

Edgar J. Lownes, Jr., and Miles O. Gibson, Providence, R. I., assignors to American Silk Spinning Co., Providence, R. I., a corporation of Rhode Island

Application June 17, 1935, Serial No. 27,094

6 Claims. (Cl. 19—146)

This invention relates to an improved ornamental yarn and method of producing the same, an object being to provide a desirable form of yarn in which is embodied a desired quantity of rabbit's hair or other substantially similar material.

Another object in view is to provide an improved method wherein a number of materials including rabbit's hair are treated in a certain order until the material is finally ready for spinning, the method of combining the material causing the parts to properly adhere or remain together in a desired and specific proportion.

An additional object is to provide an improved method of using the nubby part of silk yarn with rayon fibres and a mixture of wool and rabbit's hair to form a roving ready for spinning and with substantially specific proportions of the various materials in the complete roving.

20 In the accompanying drawings—

Figure 1 is a diagram showing the various steps of the process whereby a finished roving is produced ready for a spinning machine;

Fig. 2 is a view principally formed as a diagram showing a machine known as a rotary drawing machine with certain parts changed to produce steps in the method;

Fig. 3 is a view similar to Fig. 2 but showing a standard arrangement of the drawing machine illustrated in Fig. 2;

Fig. 4 is a diagram with certain parts in section showing a gilling machine of an old and well-known type;

Fig. 5 shows a faller or comb forming part of the gilling machine shown in Fig. 4, the same presenting an improved construction of faller especially adapted for producing yarn according to the present method;

Fig. 6 is an elevation of a short section of yarn constructed according to the present invention, the same being on an enlarged scale;

Fig. 7 is an elevation of a short section of the yarn shown in Fig. 6 greatly enlarged.

The accompanying drawings disclose diagrams indicating certain machinery arranged to produce the desired steps in the method of forming an ornamental yarn having certain proportions of certain materials. It will be evident, however, that the proportions may be varied without changing the method, but for the purpose of description specific proportions will be set forth where it is necessary to bring out certain steps in the process.

Referring particularly to Fig. 1 it will be seen that there are four principal groups of machines

used in carrying out the present method, the first group being indicated by the letter A, while the other groups are indicated respectively by the letters B, C and D.

In forming the ornamental yarn, as shown in Figs. 6 and 7, a certain quantity of waste silk, a part of which forms what is known as the nubby part of the yarn, is taken and placed in a degumming machine, indicated by the numeral 5. At the same or some other time a certain proportion of wool and rabbit's hair is dumped into a device, the same being known as an opener, indicated at 6. In the specific example given in the drawings there is forty-five per cent wool (sheep) and fifty-five per cent rabbit's hair.

At the same time these operations are taking place, or at some other time, a supply of rayon tops is dumped into a dyeing apparatus 7. The rayon tops consist of a supply of rayon filaments of various lengths usually arranged in a pile and giving the appearance of waste. These tops being of various lengths and placed in a pile become more or less matted and in order to use the same they must be dyed and then straightened out and arranged in a comparatively small band or sliver. To do this a desired supply of rayon tops is dumped into the dyeing machine 7 as above mentioned and after they have been properly dyed and later dried, the dyed rayon tops are fed into a gilling machine 8, which straightens out the fibers and arranges the supply in a long sliver which is discharged from the machine. In the illustration shown, a sliver weighs 330 grains per five and one-half yards.

As far as the present invention is concerned, the dyeing apparatus is of any desired kind and also as far as the present invention is concerned the gilling machine 8 is an ordinary gilling machine now in common use in factories which spin silk, rayon and the like. This machine takes the mass of rayon tops fed therein and straightens the filaments out to a certain extent and then feeds the tops out in a continuous band commonly known as a sliver. This band may vary in thickness and width, and is fed into a receptacle known as a can. When one can is filled the sliver is broken off and as the sliver continues to feed from the gilling machine it is discharged into a second can. When the second can is filled, the same operation takes place and the sliver is fed into a third can. This operation continues as long as the machine is in use. The slivers in all these cans will be of substantially the same weight per yard.

While the above-mentioned action is taking

place, the mass of matted wool and rabbit's hair dumped into the machine or opener 6 is being operated on in the usual manner. The machine 6 is the ordinary machine known as an opener in the industry and functions in the usual way of an opener, as above set forth. Generally speaking, this opener pulls the matted mass of rabbit's hair and wool and mixes the same somewhat. During the pulling operation it loosens up all the lumps or thickened matted parts so that when the mixture is discharged from the opener 6 it is a loose mass of wool and rabbit's hair more or less mixed.

To secure a better mixture and also to be sure that there are no undesirable lumps in the mass, the material from the opener 6 is discharged into a second opener 9 where the same operation takes place.

From the second opener the material is fed into a carding machine 10. This is an ordinary carding machine used in carding cotton, wool and the like, and the detail structure forms no part of the present invention as any desired type of carding machine may be used. When the carding machine 10 is in use it discharges a sliver of a certain weight per yard according to the way the parts are set. This sliver is fed into cans in the same way as the sliver from the gilling machine 8. It will be understood that new cans must be supplied from time to time as long as the carding machine 10 is functioning. As shown in Fig. 1, four canfuls of the slivers from the carding machine 10 are placed near the drawing machine 11 and the slivers fed into this drawing machine. This drawing machine is an old and well-known structure and is of the type shown in Fig. 3.

As used in the group B and indicated by the numeral 11, the rotary drawing machine is of the usual kind functioning in the usual way to combine, straighten, and blend the four slivers fed therein so that only one sliver is fed therefrom which is approximately the same weight as any one of the slivers fed therein. This action causes the wool and rabbit's hair to become more or less entwined; also it pulls out the material so that substantially the same proportion of wool and rabbit's hair is found within the discharged sliver as is indicated above in connection with the opener 6.

In order to secure a better and more uniform sliver and one of the desired weight, a second rotary drawing machine 14 is used and four canfuls of slivers from the drawing machine 11 are arranged near the drawing machine 14 so that the slivers therefrom may be fed therein. From the drawing machine 14 the finished sliver is discharged. This sliver, as indicated in the drawings, has a weight of 330 grains per five and one-half yards and is complete as far as group B is concerned.

While the operations above described have been taking place, or at some other time, the nubby part of the silk yarn as a waste is dumped into the degumming machine 5. This waste may be ravelings or left-over straps from silk mills, or may be cocoons which have been broken up and shredded more or less, or a mixture of cocoons and waste from silk mills. The waste is more or less matted and also contains gum, grease, and the like. When dumped into the degumming machine it is cleaned of all the objectionable matter. The degumming machine 5 may be any of the usual degumming machines on the market and is merely a vat filled with hot or boiling water containing soap or other ingredients. This treat-

ment is carried out until the gum on the natural silk and the grease on the silk from the mills are removed. This cleaned and degummed silk is still in a more or less matted or massed condition and is then dried. The drying operation may be carried out in any way. Usually a mass of the silk is placed in a rotary dryer, which is sometimes known as a whizzer. It is then removed to a hot room where the drying operation is completed.

After the material is dried it is fed into an opener 15 which is similar to the openers 6 and 9. The opener 15 pulls the matted material apart and loosens the same up to such an extent that there are no large lumps or matted parts, but the mass is loose and ready for the filling machine 16. From the opener 15 the mass of material is fed into the filler which is an old and well-known construction. The filler briefly is a device for placing a supply of filaments into what is known as "sticks", which consists of a pair of clamping bars adapted to clamp a bunch of the material. These filled sticks are then mounted in a dressing machine 17, which dressing machine is of the usual and well-known kind now in common use. This dressing machine removes the longer fibers which are known as the first draft. These longer, or rather longest, fibers are not used for the yarn disclosed in Fig. 6.

All the yarn remaining from the dressing machine not in the first draft is fed into a filling machine 18, where it is placed on sticks as above described, and these sticks are placed in a second dressing machine 19, which acts in a similar manner to the dressing machine 17. The longest fibers from the dressing machine 19 are removed to a desired point and are not used for the yarn disclosed in Fig. 6.

All the yarn not in the second draft is fed into a third filling machine 20, which acts in a similar manner to the filling machines 16 and 18, and the filled sticks from the machine 20 are placed in a third dressing machine 21, which acts in a similar manner to the first two dressing machines and discharges the third draft which is the third longest fibers.

The remaining fibers from the third draft are removed and form a mass known as "noils", indicated in Fig. 1 by the numeral 22. These noils are merely dumped into a pile and when desired to complete the process these noils are run through a dyeing machine 23 of any desired kind. The noils 22 are the shortest fibers and form little knobs or twisted bunches. The noils are more or less kinked or curly and when dyed this characteristic is increased so that they retain rather tenaciously their bunched condition. After the noils have been dyed they are fed into a carding machine 24 which is of the usual kind and similar to the carding machine 10. It will be understood that they are fed in a mass into the carding machine but leave in a band or sliver 25. This band or sliver 25 is comparatively heavy per yard and is fed into a rotary drawing machine 26 which is similar to the drawing machines 11 and 14. The sliver from the drawing machine 26 is fed into a second rotary drawing machine 27 which further straightens the fibers and then discharges them as a sliver, said sliver being fed into a third drawing machine 28. All the drawing machines act in a similar manner for drawing and reducing the diameter of the sliver, while, at the same time, they straighten more or less the fibers of the noils which overlap each other and are more or less entwined. The drawing ma-

chines 26 and 28 are set as shown in Fig. 2. The band or sliver passing from the last drawing machine, namely, drawing machine 28, is the finished sliver as far as this part of the process is concerned, and in the above example when dyed has a weight of 180 grains per five and one-half yards. It will be evident that the dyeing machine 23 could be eliminated and the remaining steps of the process carried out. When this occurs the finished sliver from the drawing machine 28 would have the natural color of the silk. The sliver from the drawing machine 28 is discharged into cans as heretofore described in respect to certain other parts.

For completing the process and describing the proportions in the example given, one can from the drawing machine 28 is placed adjacent the gilling machine 29, and one can from drawing machine 14 is placed near the gilling machine 29. At the same time four cans from the gilling machine 8 are placed adjacent gilling machine 29. Slivers from all six of these cans are fed into gilling machine 29, which functions in the usual manner and combines and blends all of these slivers until the desired sliver 30 from gilling machine 29 is of approximately the same size as any one of the fibers fed therein. This is true except that the silk noil cannot be run on this standard machine and the desired results secured. Therefore, it is necessary to change a gill box from the standard type to a type of machine that will run both the rayon and rabbit hair along with the silk noil. This requires a machine with the combined features of the standard machine and a machine that will run the silk noil without intermixing the clusters of colored fiber. This is accomplished by removing the standard fallers and replacing these fallers with special fallers 46 shown in Figure 5.

The rayon and rabbit hair sliver is run through that part of the faller that contains the standard pinning 43, and the silk noil is run through that portion of the faller containing the open or special pinning 44. Thus, on the same machine and in the same operation, the two combinations of fiber are blended into one sliver without any alteration in the required characteristic of the different fiber. Five cans of slivers from the gilling machine 29 are arranged adjacent the rotary drawing machine 31 and the slivers fed therefrom. This drawing machine combines and draws out the slivers until the discharged sliver 32 is of approximately the same size as any one of the slivers fed into the machine. Five cans of slivers from the drawing machine 31 are then fed into a second rotary drawing machine 33. Five cans of slivers from drawing machine 33 are then fed into a rotary drawing machine and finishing head 34. All the drawing machines 31, 33 and 34 are of the usual type now in common use and function in the usual way. From the rotary drawing and finishing head 34 the finished sliver is discharged ready for roving. This roving sliver 35 is ready for the spinning machine. Usually the roving sliver 35 is wound on a spool of a well-known kind and at the proper time is placed on a desired support in a spinning machine and is spun in the usual way. After having been spun the complete yarn will appear as shown in Fig. 6.

The finished yarn is made up of the various ingredients above mentioned, namely, the nubby part of silk, rabbit's hair, wool, and rayon tops. The proportions in the finished yarn are substantially the same as disclosed in Fig. 1, so that there will be approximately four parts of rayon

tops to one part of silk noils, as well as four parts of rayon tops to one part of combined wool and rabbit's hair. The rabbit's hair must be closely associated with the wool so as to hold the same in the yarn. The rabbit's hair is more or less straight while the wool is curly and wraps itself more or less around the rabbit's hair so as to bind itself into the finished yarn though part of the hair will project therefrom. However, the yarn and combined wool and rabbit's hair will extend the full length of the yarn as well as the rayon tops so that when different colors are used a very pleasing ornamental yarn will be produced having certain proportions of silk yarn, a certain proportion of combined wool and rabbit's hair, and a certain proportion of rayon tops. Where the noils are dyed red, there will be a reddish tint throughout the entire yarn, and in addition by reason of the make-up of the noils there will be lumps or enlargements 36 which are formed by certain of the noils while the rabbit's hair will have numerous hairs 37 protruding to give a fuzzy appearance to the yarn and also to the fabric produced by the yarn. It will be understood that the yarn may be woven or knit as preferred.

While the various drawing machines 31 to 34 blend and combine the material passing therethrough, nevertheless there will be in the finished yarn as shown in Fig. 6, separate fibers twisted together to form the complete yarn. Sometimes the fiber from the silk yarn dominates while at other times the combined wool and rabbit's hair dominates. In this way the exact makeup of any section of the yarn may be slightly different from the next adjacent section though in a general way they are the same. The dominant feature noticed, however, is the color scheme produced by the noils and the rabbit's hair, the noils being preferably of some rather bright color while the rabbit's hair is usually white though it could be dyed some desired color without departing from the spirit of the invention. In the general layout of Figure 1 it will be noted that the rotary drawing machine shown in Figure 2 is used as 26 and 28 while the rotary drawing machines 11, 14, 21, 31, 33 and 34 are of the type shown in Figure 3.

In regard to the machine 34, it is desired to point out that in Fig. 3 is disclosed a machine of this type which is the regular machine except that it is provided with an extra top herisson 38. The various herissons as shown in Fig. 3 act to pull, straighten, and blend more or less the various materials into the desired form of roving sliver which is almost a yarn except that it has not been twisted. This finished sliver or roving sliver is fed out through the member 39 and the guiding and pressing wheels into a can 41. From can 41 the roving sliver may be wound on a spool in any desired manner ready for the spinning machine. When the roving sliver is placed in a spinning machine and is spun in the usual manner the yarn is complete as shown in Fig. 6.

It will be understood that any dyeing is done before the materials are mixed because of the widely different materials used which would require different forms of dye. For instance, the dye for dyeing the silk noils is different from that used for dyeing rayon tops, or wool or rabbit's hair. In the example given the silk is dyed and also the rayon tops, but the wool and rabbit's hair are left undyed. As one example, it might be assumed that the rayon tops are dyed a dark red while the silk is dyed a bright red. These two shades of red with the natural color of the

wool and rabbit's hair produce a desired color scheme in the finished yarn as some of the larger noils in the finished yarn present protuberances which show up in a pleasing manner especially with the natural color of the rabbit's hair as a form of background.

We claim:

1. The method of producing an ornamental yarn consisting in treating waste silk fiber by a well-known method until the noils are removed therefrom, treating the noils until a sliver of a given weight per yard is secured, securing a supply of wool and rabbit's hair, passing the same through an opener, then passing the mixed wool and rabbit's hair through a carding machine and providing a plurality of slivers from the carding machine through a plurality of drawing machines to provide a sliver of a given weight per yard, then subjecting a supply of rayon tops to dye, then subjecting the dyed rayon tops to a gilling machine to produce a sliver of a given weight, then feeding a plurality of slivers from the gilling machine into a second gilling machine at the same time a silk sliver and a combined wool and hair fiber sliver are fed therein, then subjecting the material after it leaves the second gilling machine to a number of rotary drawing machines until a roving sliver ready for the spinning machine is produced, and finally spinning the roving sliver in a well-known manner.

2. The method of forming an ornamental yarn of silk, wool, rabbit's hair, and rayon tops, consisting in treating the rayon tops until a sliver of a given weight is produced, mixing and treating wool and rabbit's hair until a sliver of the same weight as the rayon-top sliver is produced, treating silk waste fiber until a sliver of noils is produced of approximately half the weight of the rayon-top sliver, feeding one silk sliver, one combined rabbit's hair and wool sliver, and a plurality of slivers of rayon tops into a gilling machine, taking a plurality of slivers from the gilling machine and passing the same through a drawing machine, then taking the resultant slivers and running a plurality thereof in succession through a plurality of drawing machines, the last drawing machine being a finishing head, and finally running a sliver from the finishing head through a spinning machine to produce the finished yarn.

3. The method of forming a yarn of silk, wool, rabbit's hair and rayon with at least one of said ingredients being of a different color from the remaining ingredients, consisting in forming a

sliver of a given weight of rayon, forming a sliver of combined wool and rabbit's hair of substantially the same weight per yard as the sliver of rayon, forming a sliver of silk of less weight per yard than the rayon sliver, forming a mixed sliver of the rayon, silk and wool and rabbit's hair slivers, subjecting the mixed slivers to a drawing action until the mixed slivers form a single sliver of the desired weight per yard with at least one of the individual slivers still rec-

5

ognizable by reason of its color, and finally subjecting the final sliver to a spinning machine.

4. The method of forming a yarn of silk, wool, rabbit's hair and rayon, consisting in forming a sliver of rayon, forming a sliver of wool and rabbit's hair of substantially the same weight as the sliver of rayon, forming silk noils from a supply of silk fiber, forming a sliver of silk noils of approximately one-half the weight per yard as the rayon sliver, forming a mixed sliver of the rayon, silk and wool and rabbit's hair slivers, and finally subjecting the mixed sliver to the action of a drawing machine until the mixed sliver is of a desired weight per yard.

5. The method of forming a yarn of not less than four ingredients with at least one of the ingredients being of a different color from the remaining ingredients including silk noils consisting in forming a sliver of one of said ingredients of a given weight per yard, forming a second sliver of a mixture of two of said ingredients, said second sliver being of approximately the same weight per yard as the first mentioned sliver, forming a sliver of said silk noils of appreciably less weight per yard than the first mentioned sliver, blending said slivers by subjecting all of the slivers simultaneously to a drawing action, said blending action being carried out until all of the slivers are mechanically intermingled but with one sliver still individually recognizable by reason of its color.

6. The method of forming a roving strand from silk, wool, rabbit's hair, and a fourth ingredient consisting in forming silk noils from a supply of silk fibers, forming a sliver from said noils, mixing a supply of sheep's wool and rabbit's hair, forming a sliver from the mixed sheep's wool and rabbit's hair, forming a sliver of said fourth ingredient, then subjecting all of said slivers at the same time to the action of a drawing machine for forming a finished roving strand ready for spinning.
